US00D697884S

(12) **United States Design Patent** (10) **Patent No.:** **US D697,884 S**
Lee (45) **Date of Patent:** **** Jan. 21, 2014**

(54) **TV RECEIVER**

(71) Applicant: **Sang-Young Lee**, Gwangmyeong (KR)

(72) Inventor: **Sang-Young Lee**, Gwangmyeong (KR)

(73) Assignee: **Samsung Electronics Co., Ltd.**,
Suwon-si, Gyeonggi-do (KR)

(**) Term: **14 Years**

(21) Appl. No.: **29/455,494**

(22) Filed: **May 21, 2013**

Related U.S. Application Data

(63) Continuation of application No. 29/426,428, filed on Jul. 5, 2012, now Pat. No. Des. 685,337.

Primary Examiner — Raphael Barkai

(74) *Attorney, Agent, or Firm* — Flynn, Thiel, Boutell & Tanis, P.C.

(57) **CLAIM**

The ornamental design for a TV receiver, as shown and described.

DESCRIPTION

FIG. 1 is a top front perspective view of a TV receiver showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating portions of the TV receiver are for environmental purposes only and form no part of the claimed design.

1 Claim, 4 Drawing Sheets
